UNITED STATES PATENT OFFICE.

HEMAN OSBORNE, OF SPRINGFIELD, MASSACHUSETTS.

TRANSOM-LIFTER.

1,040,570.

Specification of Letters Patent.

Patented Oct. 8, 1912.

Application filed May 24, 1911. Serial No. 629,106.

To all whom it may concern:

Be it known that I, HEMAN OSBORNE, a citizen of the United States of America, and resident of Springfield, in the county of 5 Hampden and State of Massachusetts, have invented certain new and useful Improvements in Transom-Lifters, of which the following is a full, clear, and exact description.

This invention relates to improvements in transom operating devices of a type such as is exemplified in Letters Patent of the United States granted to me June 11, 1907, No. 856,288, and one having the respective 10 functions of such a device. But the present invention is for the purpose of providing a transom operating mechanism which, due to the improved organization thereof is capable of the fulfilment of its functions more 15 efficiently and satisfactorily, and which by reason of its simplified character is less costly of manufacture and assemblage, and is less liable of derangement after protracted use and is generally of greater acceptability in the trade.

The principal features of improvement and advantage in the present device are found in the means whereby the worm-wheel carrying shaft, having the transom 20 operating lever-like member permanently fixed thereon, and radially extended therefrom, may be revolubly adjusted relatively to the worm mechanism so that the transom operating member may have all required capability for positioning or adjustment to accord with transoms which may be more or 25 less deeply set in the casings, and all as hereinafter fully explained; in the arrangement of the springs operatively employed for 30 counterbalancing the weight of the opening transom, and the means for varying the tension or reaction of the springs to insure proper counterbalancing action with respect to transoms of different sizes and weights; 35 and in the new arrangement or combination of the parts for the requirement of extreme simplicity cheapness and operative efficiency 40 of the device.

The invention is described in conjunction 45 with the accompanying drawings and is set forth in the claims.

In the drawings: Figure 1 is a front elevation of the transom operating device with the cover portion of the casing removed. 50 Fig. 2 is a vertical sectional view through the same on the line 2—2, Fig. 1. Fig. 3 is

a horizontal cross section on line 3—3, Fig. 1. Fig. 4 is a perspective view showing the operating device as applied in its operative relation to an under pivoted or hinged transom. Fig. 5 is a perspective view of the rear portion of the casing as seen from the rear. Fig. 6 is a perspective view of certain of the principal parts of the novel device in separated relations. Figs. 7 and 8 respectively are sectional and face views indicating the manner of the permanent connection of the transom operating member with the rotative carrying shaft thereof. Fig. 9 is a view of one of the counterbalancing 70 springs employed in the device.

Similar characters of reference indicate corresponding parts in all of the views.

In the drawings, A represents the supporting frame of design and dimension having fitness to its purpose, and B represents a shaft rotatively mounted in the frame and carrying at its one end which extends outwardly beyond the frame and its inclosing casing C, the lever-like member D which is 80 operatively connected with a slotted bracket E affixed on the transom in a manner common in devices of this kind.

The end portion of the shaft is made with a flange-like enlargement *a* which includes 85 a squared portion *b* and a shoulder *b*² fitted to which is the butt end of the transom operating member D which is permanently held in place by the screw *c* and retaining washer *c*². The middle portion of the shaft 90 B has the screw threads *d* thereon and other portions of the shaft toward the opposite ends thereof are made with the right and left screw threads *f*, *f*, as shown in Figs. 3 and 6. The worm-wheel F is screw engaged 95 on the threaded portion *d*, at the middle of the shaft, whereby the shaft is rotatively adjustable within, and relatively to, the worm-wheel for revolubly adjusting the transom operating member B so that such 100 member may reach its engagement with the fixture E of the transom irrespective of whether the latter is much or little inset within the casing.

It will be here explained that in the employment of the device the frame, which is inclosed by the casing C and which supports the mechanism, is generally secured on the face of the door casing about as represented in Fig. 4,—the lever-like arm D extending 105 upwardly to proximity with the transom which it, such arm, engages through the 110

medium of the slotted bracket or transom fixture E. Inasmuch as in different situations the "reveal" varies, that is in some cases the transom is set at a considerable distance back from the face of the door casing while in other cases the transom stands well forward relatively to the face of the casing, it is necessary to make provision whereby the lever-like transom-operating arm may be revolvably adjustable about the axis of the shaft B so that it will have its range of movement for forcing the transom open or closed within whatever space may be requisite according to the conditions under which the transom and the casing are set.

15 G G represent a pair of arms having apertured shanks which embrace the shaft B at opposite sides of, and closely alongside the worm-wheel F, the same being engaged with the worm-wheel so as to have revoluble movements in unison therewith by the engagement in the sockets g in the arms of the studs g' which extend from opposite sides of the worm-wheel.

20 25 J J represent a pair of ring-nuts screw engaged on the right and left threaded portions f f of the shaft and serving both to confine the shanks of the arms G G against the opposite faces of the worm-wheel and to lock the worm-wheel and shaft in their revolvably adjusted relations. These ring-nuts have holes therein to receive the engagement of a spanner-wrench. The worm-wheel meshes with the worm K mounted in 30 suitable journals in the frame and having, as a fixed part thereof, a sprocket wheel L around which runs the intermediate part of the sprocket chain M, through means of which the device is manually operated to 35 open or close the transom in a well known manner.

40 45 i represents a bar mounted in the frame above, and parallel with, the shaft B, and j j represent a pair of spiral springs having the coils thereof loosely encircling said bar and having their extremities 10 and 12 extending angularly from the bar and in angular relations to each other as best shown in Fig. 2.

50 55 60 65 Duplicated links m m connect the extremities 10 10 of the springs j with the hook-shaped ends of the arms G; and the screw-plugs o o engaged through an upper front portion of the frame have tension varying engagements with the adjacent extremities 12 12 of the springs so that by turning the screw-plugs inwardly the reaction of the springs is increased to accord with large or heavy transoms while the forward turning of the screw-plugs decreases the spring reaction. In this connection it is to be perceived that the springs j j—which are loosely coiled around the bar i and have their forward extremities engaged with the links G, will become more "wound up" and the re-

action or tension thereof increased when their upper tangential extremities 12 are rearwardly forced by the threading inwardly of the screw plugs o o,—the reversal of such conditions following a forward adjustment of the screw plugs.

70 75 80 85 90 When it is desired to vary the normal direction of the extension of the radial lever-like transom operating member D relatively to the axis of the shaft B it is only necessary on the removal of the front section of the cover or casing to loosen one or the other of the nuts J and swing the member D which is screw engaged with and permanently connected to, the shaft, so that the shaft may be rotated, as much as desired, it being understood that the threaded part d at the middle of the shaft when both of the nuts are not set up against the opposite faces of the worm wheels, is free to have a rotative movement relatively to the worm wheel, which will remain stationary by the interlocking engagement therewith of the worm K.

95 100 105 110 115 Almost the entire mechanism of the transom operating device, including the means for the adjustment of the shaft, is inclosed, concealed and safeguarded within the casing; and as none of the parts of the operative mechanism especially including those for effecting adjustments are visible or accessible, the transom operating device having the parts thereof properly positioned and mounted in use may be relied upon for indefinitely continued and efficient service without liability of derangement. It may be also stated that the operating chain the middle of which has a supporting engagement around the sprocket wheel, and the depending portions of which terminate at about the same distance below the casing, under the capabilities hereinabove described for the adjustment of the shaft, undergoes no change relatively to the sprocket wheel when the arm carrying shaft may be adjusted preparatory to setting up the device and after the chain has been assembled in relation to the sprocket wheel.

I claim:—

115 120 125 130 1. In a transom operating device, the combination with a supporting frame, and a shaft, rotatively mounted therein, having a portion thereof screw threaded, and having a transom operating arm affixed on the end thereof, of a worm-wheel having a central screw threaded opening, and screw engaged on the threaded portion of the shaft, whereby the shaft is rotatively adjustable within the worm-wheel for varying the direction of the extension of the arm, means for confining the screw engaged worm-wheel and shaft in their adjustments, a worm mounted in the frame and in engagement with the worm-wheel, and means for rotating the worm.

2. In a transom operating device, the combination with a supporting frame, and a shaft, rotatively mounted therein, having the middle portion thereof screw threaded, having opposite end portions thereof provided with right and left screw threads, and having a transom operating arm affixed on the end thereof, of a worm-wheel having a central screw threaded opening, and screw 5 engaged on the threaded middle portion of the shaft whereby the shaft is rotatively adjustable within the worm-wheel, nuts screw 10 engaging on the right and left threaded portions of the shaft and operative to lock the screw engaged worm-wheel and shaft in 15 their adjustments, a worm mounted in the frame, and in mesh with the worm-wheel, and means for rotating the worm. 20
3. In a transom operating device, in combination, a supporting frame, and a shaft rotatably mounted therein, having a transom operating element affixed on the end thereof, carrying a radial arm at a portion thereof in the frame, and having a worm-wheel thereon, a worm in mesh with the worm-wheel, and a means for rotating it, a spring supported in the frame, and a link 25 connecting said spring and said arm. 30
4. In a transom operating device, the combination with a supporting frame, and a shaft rotatably mounted therein, having a transom operating element affixed on the end thereof, carrying a radial arm at a portion thereof within the frame, and having a worm-wheel thereon, of a worm in mesh 35 with the worm-wheel, and a means for rotating it, a spring supported in the frame, a link connecting said spring with said arm, and means for varying the tension of the 40 spring. 45
5. In a transom operating device, in combination, a supporting frame, and a shaft, rotatably mounted therein, having opposite end portions thereof provided with right and left screw threads, and having a transom operating member affixed on the end thereof, a worm-wheel engaged on the middle portion of the shaft, a pair of arms having apertured shanks, embracing the shaft 50 at opposite sides of the worm-wheel, nuts screw engaged on the right and left threaded portions of the shaft and binding the shanks of said arms facewise against the worm-wheel, a pair of springs supported in the 55 frame, links connecting the springs with said arms, a worm mounted in the frame in mesh with the worm-wheel, and means for turning it. 60
6. In a transom operating device, in combination, a supporting frame, and a shaft, rotatably mounted therein, having the middle portion thereof screw threaded, having opposite end portions thereof provided with right and left screw threads, and having a transom operating member affixed on the 65 end thereof, a worm-wheel screw engaged on the threaded middle portion of the shaft, a pair of arms having apertured shanks, embracing the shaft at opposite sides of the worm-wheel, nuts screw engaging on the right and left threaded portions of the shaft 70 and binding the shanks of said arms against the sides of the worm-wheel, a pair of springs supported in the frame, links connecting the springs with said arms, and screws engaged through the frame and engaged with, and for varying the tension of, said springs, and worm mounted in the frame and meshing into the worm-wheel and means for turning it. 75
7. In a transom operating device, in combination, a supporting frame, a shaft, rotatively mounted therein, having opposite end portions thereof made with right and left screw threads, and having a transom operating member affixed on the end thereof, a worm-wheel engaged on the middle portion of the shaft, and provided with studs 80 projecting from opposite sides thereof, a pair of arms having apertured shanks embracing the shaft at opposite sides of the worm-wheel, and having sockets in which said studs are engaged, nuts screw engaged on the right and left threaded portions of the shaft 85 and confining the shanks of said arms against the sides of the worm-wheel, a pair of springs supported in the frame, links connecting the springs with said arms, and a worm, mounted in the frame, and meshing with the worm-wheel, and means for turning it. 90
8. In a transom operating device, in combination, a supporting frame, a shaft, rotatively mounted therein, having a transom operating member affixed on the end thereof, 95 and carrying a radially extending arm, means for imparting rotative movements to said shaft, a spring mounted in the frame, and a link connecting said arm with said spring. 100
9. In a transom operating device, in combination, a supporting frame, a shaft rotatively mounted therein, having a transom operating member affixed thereon, and carrying a radially extending arm, means for 105 imparting rotative movements to said shaft, a spring mounted in the frame, a link connecting said arm with said spring, and means for varying the tension of the spring. 110
10. In a transom operating device, in combination, a supporting frame, a shaft rotatively mounted therein, provided with a transom operating member, and carrying a radially extending arm, means for rotating said shaft, a bar mounted in the frame, a spiral spring having the coils thereof encircling said bar, and having the extremities thereof extended angularly from said bar, a link connecting one extremity of the spring 115 with said arm, and a screw engaged through 120
- 125
- 130

the frame, and having a tension-varying engagement with the other extremity of said spring.

11. In a transom operating device, in combination, a supporting frame, a shaft rotatively mounted therein, having its middle portion screw threaded, having opposite end portions thereof made with right and left screw threads, and having a transom operating member affixed on the end thereof, a worm-wheel screw engaged on the middle portion of the shaft, a pair of arms having apertured shanks embracing the shaft at opposite sides of the worm-wheel, nuts screw engaged on the right and left threaded portions of the shaft, and serving both to confine the shanks of said arms against the opposite faces of the worm-wheel, and to detachably lock the worm-wheel and shaft in their rotational adjustable relations, a bar mounted in the frame parallel with the shaft, spiral springs having the coils thereof encircling said bar, and having their extremities extending angularly from the bar, links connecting an extremity of each spring with each arm, screws engaged through the frame and having tension-varying engagements with the other extremities of said springs, a worm rotatively mounted in the frame, and

in mesh with said worm-wheel, and means for turning said worm.

12. In a transom operating device, the combination with a supporting frame, and a shaft, rotatively mounted therein, having portions at either side of its intermediate portion provided with right and left screw threads, and having a transom operating arm affixed on the end thereof and extended radially therefrom, of a worm-wheel having a central opening, and engaged about the intermediate portion of the shaft whereby the shaft is rotatively adjustable within and relatively to the worm-wheel, for varying the direction of the extension of the radial arm relatively to the axis of the shaft, nuts screw engaging on the right and left threaded portions of the shaft and operative to lock the screw engaged worm wheel and shaft in their adjustments, a worm mounted in the frame, and in mesh with the worm-wheel, and means for rotating the worm.

Signed by me at Springfield, Mass., in presence of two subscribing witnesses.
